VALVE MECHANISM FOR EXPLOSIVE ENGINES

Anthony A. Smith, Chicago, Ill.

Application August 25, 1933, Serial No. 686,786

11 Claims. (Cl. 123—90)

My invention relates to internal combustion engines, and more particularly to the valve mechanism therefor, and my main object is to provide a novel valve which will create a considerable improvement in the efficiency of the engine.

A further object of the invention is to utilize the standard poppet valve with a development which maintains the valve in open position much longer than usual, thereby providing a clear passage for the incoming or outgoing gases for a longer time.

A still further object of the invention is to procure the opening of a passage for the gases entering or leaving the engine cylinder much quicker than under the present practice, yet without increasing the stroke of the valve.

Another object of the invention is to associate a movable seat with the poppet valve, and provide means for the co-operation of the valve with the seat by a reduced movement in the controls thereof.

An additional object of the invention is to provide an installation which requires less room in the cylinder head, enabling the same to be made with a smaller valve pocket.

With the above objects in view, and any others that may suggest themselves from the specification and claims to follow, a better understanding of the invention may be had by reference to the accompanying drawing, in which—

Fig. 1 is a section of a typical internal combustion engine, showing the novel valve mechanism in closed position;

Fig. 2 is a view similar to Fig. 1, showing the valve mechanism in open position; and

Figs. 3, 4 and 5 are, respectively, enlarged sections on the lines 3—3, 4—4 and 5—5 of Fig. 1.

In the analysis of poppet valve action in the typical internal combustion engine, it is found that the greater movement of the valve entails the opening and closing actions of the same, and the valve is only fully open for a very brief period at the peak of its movement. Thus, the passage for the gases entering or leaving the engine is practically always changing in area and is generally restricted in cross section. This fact materially affects the velocity of the medium in the passages and reduces the efficiency of the engine. To remedy this condition, the cams operating the valves would have to be made considerably steeper, which would make it more difficult to raise the valves and would tend to jam or distort the stems thereof. It has therefore been my intention to provide a valve mechanism which by

means of the movable seat mentioned enables me to impart only half the stroke to the valve, yet secure the full opening thereof, so that I am able to use a flatter cam and so keep the valve open much longer than heretofore.

In carrying out the invention, a specific reference to the drawing shows the engine cylinder at 10, the piston at 11, the cylinder head at 12, the poppet valve therefor at 13, the valve pocket at 14, the valve guide at 15, the valve port at 16, the valve spring at 17 and the cam shaft at 18.

In the novel embodiment, the valve pocket 14 is cylindrically machined to afford the disposal of a sliding, piston-type of seat 19 for the valve head 13a. As shown in Fig. 2, the seat 19 is chamfered on the inside as is the usual practice to seat the valve at 13a; and the wall of the seat-piston is provided with rings 19a to seal it in the pocket 14.

I prefer to provide the stem of the valve 13 with a roller 13b at its lower end to ride on the shaft 18 and the cam 18a thereof. When the valve is seated as in Fig. 1, the upper part of its stem seats in an internal shoulder 15a of the valve guide 15, from which region downward the valve stem is somewhat reduced in diameter, as shown. The shoulder 15a merely forms a limit for the descent of the valve, in case the seat 19 should be removed or lowered for any reason, and such shoulder is calculated not to form a stop before the valve head 13a is fully seated on its seat.

Sufficient clearance is had between the origin of the valve stem reduction and the shoulder 15a, as well as between the roller 13b and the cam shaft 18, to allow for the very slight fall of the valve when it is ground. Of course, where the valve requires refacing or re-seating, the guide shoulder 15a will require cutting down somewhat. In such a case the valve itself could be altered to include an adjustable tappet arrangement at the bottom for the necessary clearance from the cam shaft and its cam, or replaced by a valve made with such an arrangement.

It is my intention that the seat 19 descend when the valve 13 rises, in keeping with the principle of giving the valve only half the usual stroke while forming a passage of the same cross section as with a standard valve. For this purpose, I extend the seat piston 19 downwardly with a set of four stems 20, which pass slidably through guides 20a formed in the cylinder casting. The stems 20 connect with the upper end 21a of a rectangular member 21 extending in a downward direction, such member having a base 21b boosted from underneath by a coil spring 55

22. The base 21b has companion ledges 21c upon which bear twin cams 18b carried by the cam shaft 18. Thus, while the cam 18a bears upwardly on the valve stem 13 against the tension 5 of the valve spring 17, the twin cams 18b bear downwardly upon the member 21 against the tension of the spring 22, the effect of these actions being to raise the valve head 13a while its seat 19 is lowered.

10 Owing to the fact that the valve head and seat separate simultaneously to create a given opening, only half of the usual stroke is necessary for either the valve or the seat, enabling the cams 18a and 18b to be made lower and therefore much flatter than usual. I can thus procure the opening of the valve passage in about 45° of crank shaft travel, then have a full opening for 90°, and the closing for the final 45° of the 180° valve-operating interval.

15 20 It will be obvious from the above description that I have provided a valve mechanism which in opening the valve more quickly and keeping it open much longer than usual will considerably improve the charging and scavenging of the cylinder, and thus procure greater power and speed.

25 Further, the more gradual opening of the valve will greatly reduce the detonation and noise of the engine. Further, the action and opening procured by the novel valve will permit it to be 30 made of smaller diameter, therefore requiring a smaller valve pocket. Further, the opening and closing actions of the novel valve will be more certain because of the shorter and more gradual climb and descent over the cam, making the valve 35 more reliable for the functions mentioned than valves of the present type, where the control is in the nature of an impact, tending to continually keep the valve off its seat. The full and certain closing of the valve is also insured by the 40 fact that the descent thereof is through a much shorter space than usual, thus facilitating early seating. Finally, it will be apparent that the parts entering into the novel valve mechanism are in keeping with standard engineering practice and devoid of delicate elements or complicated mechanisms, enabling the valve to operate 45 efficiently for long periods without undue attention or repair.

I claim:—

- 50 1. An engine containing a valve, a pocket for the latter, a seat for the valve and slidable in the pocket toward and from the head of the valve, an engine camshaft, and means controlled by the latter to open the valve and retract the seat simultaneously.
- 55 2. An engine containing a poppet valve having a valve head, a valve stem and a valve pocket; a seat for said valve slidable mounted in said pocket for movement towards and away from said valve head, cam contacting means on the free end of said valve stem, a cam shaft, a cam 60 on said shaft for contacting said valve stem and actuating said valve head in one direction, an extension of said sliding seat, said extension extending alongside of said valve stem and beyond the end thereof to a point beyond said cam shaft, cam contacting means on the end of said extension, and a second cam means on said cam

shaft and arranged to contact said extension simultaneously with the contact of the first cam with said valve stem.

3. The structure of claim 2, said second named cam means being on the opposite side of the camshaft from said valve cam and staggered from the latter.

4. The structure of claim 2, said second named cam means comprising spaced cams on the opposite side of the camshaft from said valve cam, 10 and follower elements on the extension for the spaced cams, said elements by being spaced accordingly affording clearance for the valve cam.

5. The structure of claim 2, and a spring urging the extension into engagement with said second named cam means.

6. The structure of claim 2, the extension comprising rods directed from the seat-cylinder, bearings in the valve pocket for the slidable passage of the rods, and a rectangular frame carried by 20 the rods as a follower.

7. An engine containing a poppet valve having a valve head, a valve stem and a valve pocket; a seat for said valve slidably mounted in said pocket for movement towards and away from said valve head, cam contacting means on the free end of said valve stem, an extension of said seat, cam contacting means on said extension, a cam shaft, and separate cams on said shaft to simultaneously engage both cam contacting means and 30 impart a positive separating movement to said valve and seat simultaneously.

8. An engine containing a poppet valve, means for actuating said valve in one direction, a seat for said valve, means acting simultaneously with 35 said valve actuating means for retracting said seat in a direction opposite to that of said valve from the location where the valve normally seats upon it, a valve stem for said valve, a bearing for said stem, a stop in said bearing, and a portion of 40 said valve stem being formed to engage said stop and limit the movement of said valve and stem in the seating direction.

9. An engine containing a poppet valve, means for actuating said valve in one direction, a seat 45 for said valve, means acting simultaneously with said valve actuating means for retracting said seat in a direction opposite to that of said valve from the location where the valve normally seats upon it, a bearing for the slidable passage of the 50 valve stem, said stem being formed with a shoulder, and a seat formed in the bearing and effective to engage said shoulder and prevent excessive movement of the valve beyond its seating position.

10. An engine containing a valve, said valve having a head and a slidable seat therefor, means synchronized with said engine and positively and automatically moving said head and valve seat simultaneously in opposite directions to open said 60 valve.

11. An engine containing a valve, said valve having a head and a slidable seat therefor, and means operated by and synchronized with said engine for automatically moving said head and 65 seat simultaneously in opposite directions to open said valve.

ANTHONY A. SMITH.
